DEVICE FOR ADJUSTING THE IGNITION
TIMING OF INTERNAL COMBUSTION EN-
GINESFritz Nallinger, Stuttgart, Germany, assignor to
Daimler-Benz Aktiengesellschaft, Stuttgart-
Unterturkheim, GermanyApplication May 11, 1938, Serial No. 207,187
In Germany September 7, 1936

18 Claims. (Cl. 123—117)

The invention relates to a construction of and improvement in devices for the automatic adjustment of the ignition timing of internal combustion engines in which the adjustment of the ignition from retarded ignition to advanced ignition is controlled by a piston which is actuated on one side by a spring and on its other side by the fluid pressure of a pump dependent on the speed of the engine. The invention consists essentially in the feature that a valve-controlled return conduit branches off, in the range of the piston stroke, from the side of the pressure cylinder filled with pressure fluid for the purpose of establishing between the end positions of the control piston corresponding respectively to advanced and retarded ignition, a mean piston position corresponding to a mean ignition timing.

The above mentioned operation is obtained only in a troublesome manner with purely mechanically controlled devices, such for example as a centrifugal pendulum governor. Adjusting devices, which are controlled by sub-pressure and are simultaneously dependent on the position of the throttle valve, have the property that the sub-pressure is only conditionally dependent on speed, so that the regulating action itself is therefore in certain circumstances inaccurate. Further such a regulating device operates only with very small forces which are not sufficient for the adjustment of modern double ignition systems or would necessitate very large dimensions of the adjusting devices.

The regulating device according to the invention is operated, on the contrary, by a pressure fluid controlled by the internal combustion engine and is preferably taken from the lubricating oil circuit. Very small dimensions are satisfactory with such an adjustment device and the regulation can at the same time be controlled satisfactorily. If the pressure fluid is not taken from the lubricating oil circuit, it is necessary to use pumps which are not quite liquid-tight (pervious pumps, e. g. cog wheel pump, circulating pump) to ensure the possibility of discharging the pressure cylinder after stopping the engine. Thus always means are provided for this discharging.

As already mentioned, the pumping device for obtaining the pressure fluid is driven indirectly by the crank shaft of the engine. Between carburettor and inlet valve a throttle valve may be provided in the induction pipe. In the mentioned return conduit a stop element is provided which advantageously is connected with the throttle element in the induction pipe or connection pipe between carburettor and engine. The throttle

element may be constructed as rotary valve with a pivoted arm to which advantageously a system of rods is connected which is in operative association with a cam, carried on the spindle of the throttle valve.

Furthermore it is possible to provide as stop element in the return conduit a rotary valve which is connected with a throttle valve in the induction or in the connection pipe in such a way that it acts with delay. This is preferably constructed in such a way that the stop valve permits flow through the return conduit only after a certain adjustment of the throttle valve in direction of opening.

This delay is obtained in manners known per se, e. g.

1. By correspondingly adjusted crank-driving,
2. By a slotted connection rod between throttle valve and rotary valve;
3. By a cam-shaft or the like.

One construction of apparatus made according to the invention is illustrated in the accompanying drawing, wherein:

Fig. 1 shows the general arrangement with the parts in the position for retarded ignition.

Fig. 2 shows the ignition apparatus and the ignition adjusting device in a position for advanced ignition.

Fig. 3 illustrates the same apparatus as Fig. 2 in the mean ignition position.

Fig. 4 shows the throttle valve arrangement in a position corresponding to that of the elements of Fig. 1.

In the drawing, 1 denotes the motor, 2 its oil pump, 4 the pressure conduit of the latter, 5 the magneto of the engine, 6 the pivoted lever for the ignition adjustment, 7 a throttle valve arranged in the induction pipe of the engine and 8 the adjusting lever.

According to the invention the rod 3 of the piston 20 engages the adjusting lever 6 for the ignition adjustment, the piston 20 being loaded by a spring 9 and sliding in a cylinder 10. The spring 9 presses the piston 20 against the stop, 11, a second stop 12 limiting the stroke of the piston. A conduit 13, branching off from the oil pressure conduit 4 to the engine, communicates with the cylinder 10 in front of the piston 20. Another conduit 14 leads off from the cylinder 10 and communicates with the oil reservoir 21, from which the lubricating oil pump 2 draws off oil. A rotary valve 15 is provided in the conduit 14 and is operated through a pivoted lever 16 connected to a rod 17 the other end of which is

pivoted to the bell crank lever 18. A pin 22 carried on the rod 28 engages in the slot 19 of the bell crank lever 18. The rod 28 passes through the bearings 23 and 24 and is pressed by the spring 25 supported against the bearing 24 and the disc 27 against the cam 26 carried on the axle 29 of the throttle valve 7.

The manipulation and operation of the apparatus according to the invention is as follows.

- 10 When the engine is not running the throttle valve 7 is closed. The spring 25 displaces the rod 28 towards the left and thereby brings the valve 15 into a position in which it closes the passage through the conduit 14 (Figs. 1 and 2).
- 15 The spring 9 keeps the piston 20 in its end position to the right and the rod 3 keeps the pivoted arm 6 of the ignition adjustment in its end position to the right in which it is adjusted for retarded ignition (Fig. 1).
- 20 On starting the engine the oil pump 2 begins immediately to pump oil into the conduit 4 and into the conduit 13 and the piston 20 is thereupon displaced from the right end position (Fig. 1) into the left end position (Fig. 2), with straining 25 of the spring 9, the movement to the left being limited by the stop 12. With the movement of the piston the lever 6 is also swung into the left end position and thereby the ignition device is adjusted to advanced ignition (Fig. 2).
- 25 On further opening of the throttle valve 7 the rod 28 and the valve 15 do not immediately alter their positions, until the cam 26 acting against the straining of the spring 25 begins to displace the rod 28 to the right, to swing the arm 16 upwards and thereby to open the rotary valve 15. The pressure oil can now flow away in front of the piston through the conduit 14 and the spring 9 can be relieved to the extent permitted by the piston 20 returning into the position directly in front of the point where the conduit 14 communicates with the cylinder. The adjusting lever 6 of the ignition adjustment is thereby also returned into the mean position. This position corresponds to a mean ignition timing under full load.
- 30 The connection of the rotary valve with the throttle valve in the induction pipe is preferably carried out so that it operates with delay, so that the stop valve opens the passage of the return conduit only after a certain adjustment of the throttle valve in the opening direction.
- 35 Instead of one conduit 14 a plurality of branch pipes may also be arranged one behind the other and arranged to be closed each one by a separate stop member or by a common stop member.
- 40 It is within the scope of the invention to replace the control cam also by a pivoted connection provided with a slotted guide. Similarly the construction of the stop member in the conduit 14 may be varied within the scope of the invention.
- 45 Instead of being connected to the oil pressure conduit the regulating device may also be connected to the water cooling circuit of the engine.

Having now particularly described and ascertained the nature of my said invention and in what manner the same is to be performed, I declare that what I claim is:

1. An internal combustion engine comprising a magneto electric ignition apparatus, an adjusting device for adjusting the ignition timing from retarded to advanced ignition comprising a piston moving in a cylinder, which is loaded on the one side by a spring and on the other side by fluid pressure, a pumping device driven indirectly from the crank shaft of the engine for producing the pressure fluid, the piston pro-

viding in its one end position for advanced ignition, in its second end position for retarded ignition and in a mean position for a mean ignition timing, and a return conduit in the cylinder wall for the pressure fluid for establishing the mean piston position, means to discharge the pressure cylinder of the pumping device.

2. An internal combustion engine comprising a magneto electric ignition apparatus, an adjusting device for adjusting the ignition timing from retarded to advanced ignition comprising a piston moving in a cylinder, which is loaded on the one side by a spring and on the other side by fluid pressure, a previous pumping device driven indirectly from the crank shaft of the engine for producing the pressure fluid, the piston providing in its one end position for advanced ignition, in its second end position for retarded ignition and in a mean position for a mean ignition timing, a return conduit in the cylinder wall for the pressure fluid for establishing the mean piston position, and a stop element in the return conduit.

3. An internal combustion engine comprising a magneto electric ignition apparatus, an induction pipe for the fuel mixture between carburetor and inlet valve, a throttle valve in the induction pipe, an adjusting device for adjusting the ignition timing from retarded to advanced ignition comprising a piston moving in a cylinder, which is loaded on the one side by a spring and on the other side by fluid pressure, a previous pumping device driven indirectly from the crank shaft of the engine for producing the pressure fluid, the piston providing in its one end position for advanced ignition, in its second end position for retarded ignition and in a mean position for a mean ignition timing, a return conduit in the cylinder wall for the pressure fluid for establishing the mean piston position and a stop element in the return conduit.

4. An internal combustion engine comprising a magneto electric ignition apparatus, an induction pipe for the fuel mixture between carburetor and inlet valve, a throttle valve in the induction pipe, an adjusting device for adjusting the ignition timing from retarded to advanced ignition comprising a piston moving in a cylinder, which is loaded on the one side by a spring and on the other side by fluid pressure, a previous pumping device driven indirectly from the crank shaft of the engine for producing the pressure fluid, the piston providing in its one end position for advanced ignition, in its second end position for retarded ignition and in a mean position for a mean ignition timing, a return conduit in the cylinder wall for the pressure fluid for establishing the mean piston position, a stop element in the return conduit, said stop element being connected with the throttle valve in the induction pipe for the fuel mixture.

5. An internal combustion engine comprising a magneto electric ignition apparatus, an induction pipe for the fuel mixture between carburetor and inlet valve, a throttle valve in the induction pipe, an adjusting device for adjusting the ignition timing from retarded ignition to advanced ignition consisting of a piston moving in a cylinder which is loaded on the one side by a spring and on the other side by fluid pressure, a previous pumping device driven indirectly from the crank shaft of the engine for producing the fluid pressure, the piston providing in its one end position for advanced ignition, in its second end position for retarded ignition and in a mean position for a mean ignition timing, a return

conduit in the cylinder wall for the pressure fluid for establishing the mean piston position, a rotary valve in the return conduit as the stop element, said rotary valve having a pivoted arm.

6. An internal combustion engine comprising a magneto electric ignition apparatus, an induction pipe for the fuel mixture between carburetor and inlet valve, a throttle valve in the induction pipe, an adjusting device for adjusting the ignition timing from retarded ignition to advanced ignition consisting of a piston moving in a cylinder which is loaded on the one side by a spring and on the other side by fluid pressure, a previous pumping device driven indirectly from the crank shaft of the engine for producing the fluid pressure, the piston providing in its one end position for advanced ignition, in its second end position for retarded ignition and in a mean position for a mean ignition timing, a return conduit in the cylinder wall for the pressure fluid for establishing the mean piston position, a rotary valve in the return conduit as the stop element, said rotary valve having a pivoted arm, and a system of rods connected to the pivoted arm which is in operative association with a cam carried on the spindle of the throttle valve.

7. An internal combustion engine comprising a magneto electric ignition apparatus and adjusting device for adjusting the ignition timing from retarded ignition to advanced ignition consisting of a piston moving in a cylinder, which is loaded on the one side by a spring and on the other side by a fluid pressure, a previous pumping device driven indirectly from the crank shaft of the engine for obtaining the pressure fluid, the piston providing in its one end position for advanced ignition, in its second end position for retarded ignition and in a mean position for a mean ignition timing, a return conduit in the cylinder wall for the pressure fluid for establishing the mean piston position, and a rotary valve acting as stop element in the return conduit, said rotary valve being coupled with the throttle valve in the induction pipe by a connection acting with delay.

8. An internal combustion engine comprising a magneto electric ignition apparatus, an induction pipe for the fuel mixture between carburetor and inlet valve, a throttle valve in the induction pipe, and adjusting device for adjusting the ignition timing from retarded ignition to advanced ignition consisting of a piston moving in a cylinder, which is loaded on the one side by a spring and on the other side by a fluid pressure, a previous pumping device driven indirectly from the crank shaft of the engine for obtaining the pressure fluid, the piston providing in its one end position for advanced ignition, in its second end position for retarded ignition and in a mean position for a mean ignition timing, a return conduit in the cylinder wall for the pressure fluid for establishing the mean piston position, and a rotary valve acting as stop element in the return conduit, said rotary valve being coupled with the throttle valve in the induction pipe by a connection acting with delay.

9. An internal combustion engine comprising a magneto electric ignition apparatus, an induction pipe for the fuel mixture between carburetor and inlet valve, a throttle valve in the induction pipe, and adjusting device for adjusting the ignition timing from retarded ignition to advanced ignition consisting of a piston moving in a cylinder, which is loaded on the one side by a

spring and on the other side by a fluid pressure, a previous pumping device driven indirectly from the crank shaft of the engine for obtaining the pressure fluid, the piston providing in its one end position for advanced ignition, in its second end position for retarded ignition and in a mean position for a mean ignition timing, a return conduit in the cylinder wall for the pressure fluid for establishing the mean piston position, and a rotary valve acting as stop element in the return conduit, said rotary valve being coupled with the throttle valve in the induction pipe by a connection acting with delay which is so constructed that the stop valve permits flow through the return conduit only after a certain adjustment of the throttle valve in the direction of opening.

10. An internal combustion engine comprising a magneto electric ignition apparatus, an adjusting device for adjusting the ignition timing from retarded to advanced ignition comprising a piston moving in a cylinder, which is loaded on the one side by a spring and on the other side by fluid pressure, a pumping device connected to the lubricating oil circuit and driven indirectly from the crank shaft of the engine for producing the pressure fluid, the piston providing in its one end position for advanced ignition, in its second end position for retarded ignition and in a mean position for a mean ignition timing, and a return conduit in the cylinder wall for the pressure fluid for establishing the mean piston position.

11. An internal combustion engine comprising a magneto electric ignition apparatus, an adjusting device for adjusting the ignition timing from retarded to advanced ignition comprising a piston moving in a cylinder, which is loaded on the one side by a spring and on the other side by fluid pressure, a pumping device connected to the lubricating oil circuit and driven indirectly from the crank shaft of the engine for producing the pressure fluid, the piston providing in its one end position for advanced ignition, in its second end position for retarded ignition and in a mean position for a mean ignition timing, and a return conduit in the cylinder wall for the pressure fluid for establishing the mean piston position, and a stop element in the return conduit.

12. An internal combustion engine comprising a magneto electric ignition apparatus, an induction pipe for the fuel mixture between carburetor and inlet valve, a throttle valve in the induction pipe, an adjusting device for adjusting the ignition timing from retarded to advanced ignition comprising a piston moving in a cylinder, which is loaded on the one side by a spring and on the other side by fluid pressure, a pumping device connected to the lubricating oil circuit and driven indirectly from the crank shaft of the engine for producing the pressure fluid, the piston providing in its one end position for advanced ignition, in its second end position for retarded ignition and in a mean position for a mean ignition timing, a return conduit in the cylinder wall for the pressure fluid for establishing the mean piston position and a stop element in the return conduit.

13. An internal combustion engine comprising a magneto electric ignition apparatus, an induction pipe for the fuel mixture between carburetor and inlet valve, a throttle valve in the induction pipe, an adjusting device for adjusting the ignition timing from retarded to advanced ignition comprising a piston moving in a cylinder, which is loaded on the one side by a spring and

- on the other side by fluid pressure, a pumping device connected to the lubricating oil circuit and driven indirectly from the crank shaft of the engine for producing the pressure fluid, the piston providing in its one end position for advanced ignition, in its second end position for retarded ignition and in a mean position for a mean ignition timing, a return conduit in the cylinder wall for the pressure fluid for establishing the mean piston position, a stop element in the return conduit, said stop element being connected with the throttle valve in the induction pipe for the fuel mixture.
14. An internal combustion engine comprising a magneto electric ignition apparatus, an induction pipe for the fuel mixture between the carburetor and inlet valve, a throttle valve in the induction pipe, an adjusting device for adjusting the ignition timing from retarded ignition to advanced ignition consisting of a piston moving in a cylinder which is loaded on the one side by a spring and on the other side by fluid pressure, a pumping device connected to the lubricating oil circuit and driven indirectly from the crank shaft of the engine for producing the fluid pressure, the piston providing in its one end position for advanced ignition, in its second end position for retarded ignition and in a mean position for a mean ignition timing, a return conduit in the cylinder wall for the pressure fluid for establishing the mean piston position, a rotary valve in the return conduit as the stop element, said rotary valve having a pivoted arm.
15. An internal combustion engine comprising a magneto electric ignition apparatus, an induction pipe for the fuel mixture between carburetor and inlet valve, a throttle valve in the induction pipe, an adjusting device for adjusting the ignition timing from retarded ignition to advanced ignition consisting of a piston moving in a cylinder which is loaded on the one side by a spring and on the other side by fluid pressure, a pumping device connected to the lubricating oil circuit and driven indirectly from the crank shaft of the engine for producing the fluid pressure, the piston providing in its one end position for advanced ignition, in its second end position for retarded ignition and in a mean position for a mean ignition timing, a return conduit in the cylinder wall for the pressure fluid for establishing the mean piston position, a rotary valve in the return conduit as the stop element, said rotary valve having a pivoted arm.
16. An internal combustion engine comprising a magneto electric ignition apparatus, and adjusting device for adjusting the ignition timing from retarded ignition to advanced ignition consisting of a piston moving in a cylinder, which is loaded on the one side by a spring and on the other side by a fluid pressure, a pumping device connected to the lubricating oil circuit and driven indirectly from the crank shaft of the engine for obtaining the pressure fluid, the piston providing in its one end position for advanced ignition, in its second end position for retarded ignition and in a mean position for a mean ignition timing, a return conduit in the cylinder wall for the pressure fluid for establishing the mean piston position, and a rotary valve acting as stop element in the return conduit, said rotary valve being coupled with the throttle valve in the induction pipe by a connection acting with delay.
17. An internal combustion engine comprising a magneto electric ignition apparatus, an induction pipe for the fuel mixture between carburetor and inlet valve, a throttle valve in the induction pipe, and adjusting device for adjusting the ignition timing from retarded ignition to advanced ignition consisting of a piston moving in a cylinder, which is loaded on the one side by a spring and on the other side by a fluid pressure, a pumping device connected to the lubricating oil circuit and driven indirectly from the crank shaft of the engine for obtaining the pressure fluid, the piston providing in its one end position for advanced ignition, in its second end position for retarded ignition and in a mean position for a mean ignition timing, a return conduit in the cylinder wall for the pressure fluid for establishing the mean piston position, and a rotary valve acting as stop element in the return conduit, said rotary valve being coupled with the throttle valve in the induction pipe by a connection acting with delay.
18. An internal combustion engine comprising a magneto electric ignition apparatus, an induction pipe for the fuel mixture between carburetor and inlet valve, a throttle valve in the induction pipe, and adjusting device for adjusting the ignition timing from retarded ignition to advanced ignition consisting of a piston moving in a cylinder, which is loaded on the one side by a spring and on the other side by a fluid pressure, a pumping device connected to the lubricating oil circuit and driven indirectly from the crank shaft of the engine for obtaining the pressure fluid, the piston providing in its one end position for advanced ignition, in its second end position for retarded ignition and in a mean position for a mean ignition timing, a return conduit in the cylinder wall for the pressure fluid for establishing the mean piston position, and a rotary valve acting as stop element in the return conduit, said rotary valve being coupled with the throttle valve in the induction pipe by a connection acting with delay.
